UNITED STATES PATENT OFFICE.

LEOPOLD M. KARNASCH, OF SAN FRANCISCO, CALIFORNIA, ASSIGNOR TO THE PELTON WATER WHEEL COMPANY, OF SAN FRANCISCO, CALIFORNIA, A CORPORATION OF CALIFORNIA.

GOVERNOR.

1,173,437.

Specification of Letters Patent. Patented Feb. 29, 1916.

Application filed May 6, 1915. Serial No. 26,293.

To all whom it may concern:

Be it known that I, LEOPOLD M. KARNASCH, a citizen of the United States, and a resident of the city and county of San Francisco, State of California, have invented 5 a new and useful Governor, of which the following is a specification.

The invention relates to speed control governors for moving parts of apparatus or 10 prime movers which control the speed of the apparatus or prime mover and which parts require considerable power for their operation.

An object of the invention is to provide 15 a governor of the class described which is simple in construction and operation.

Another object of the invention is to provide 20 a governor of the class described, which operates to move the part of the apparatus to be controlled only the proper distance 25 to effect speed control and to hold the part in such position.

A further object of the invention is to provide 30 a governor of the class described in which the movement of the power operated part of the governor serves directly to place the controlling mechanism for such part in neutral position.

The invention possesses other advantages 35 features, some of which, with the foregoing, will be set forth at length in the following description where I shall outline in full that form of the invention which I have selected for illustration in the drawings accompanying and forming part of the present specification.

In the drawings I have shown only one specific form of my generic invention, but it is to be understood that I do not limit 40 myself to such form because my invention may be embodied in a multiplicity of forms, each being a species of my said invention. It is also understood that by the claims succeeding the description of my invention, I 45 desire to cover the invention in whatever form it may be embodied.

The governor of my invention is particularly applicable for use in connection with apparatus and prime movers in which the 50 movable part which controls the speed of the device requires considerable power for its operation, although it is to be understood that the governor may be employed to control the speed of any apparatus. The governor 55 is particularly applicable to the speed

control of hydraulic apparatus, such as water-wheels and turbines, in which instances it may operate to move the control valve to vary the amount of water flowing or to move the nozzle to vary the amount 60 of water projected against the wheel.

In the drawings, for the purpose of illustration, I have shown the governor connected to the needle valve of a tangential water wheel, but this is only one of the uses 65 to which the governor may be put.

Referring to said drawings: Figure 1 is an end view of the governor, partly in section. Fig. 2 is a vertical section of a portion of the governor, taken at right angles 70 to Fig. 1. Fig. 3 is a side view of the lower portion of the governor. Fig. 4 is a section of the lower portion of the governor taken at right angles to Fig. 3. Fig. 5 is an elevation showing the governor connected to a 75 tangential water wheel.

The governor comprises in general, a centrifugal governor, a regulating valve operated by the centrifugal governor, a neutralizing or return mechanism, a power cylinder 80 with its associated pistons to which the flow of the operative pressure fluid is controlled by the regulating valve, means carried by the pistons for operating the return mechanism and a power shaft connected to the 85 pistons.

The governor comprises a suitable casing 2 in which the power operating and controlling devices are arranged. Mounted on the casing is the speed controlled or centrifugal governor 3, which is provided with a pulley 4, which is connected by the belt 5 with the prime mover or other apparatus to be governed. The centrifugal governor may be of any desired form and its particular construction does not form a part of this invention. The top head 6 of the governor 90 3 is movable vertically due to variations in the centrifugal force of the governor balls due to variations in speed. The present speed governor is constructed so 95 that an increase in speed causes the top head 6 to be depressed and a decrease in speed when the governor is running allows the top head to rise. Means are also provided in the centrifugal governor for adjusting the tension on the governor balls, so that different positions of the balls may be secured for the same speed.

Secured to the top head 6 of the centrifu- 110

gal governor is a rod 7 which extends downward into the casing and which is provided on its lower end with a piston valve 8. Surrounding the piston valve and fitting closely to the pistons 12-13 thereon is a sleeve 14 which is provided with ports which are controlled by the piston valve. The sleeve 14 is slideable vertically in the chambered cylinder 15 and is pressed downward by the spring 16. The piston valve 8 and the apertured sleeve form, in combination, a valve for controlling the flow of fluid under pressure to the power operated mechanism. A movement of the piston valve relative to the sleeve, in the present construction, opens the valve and a movement of the sleeve with relation to the piston valve closes the valve. The two parts, the piston valve and the sleeve, thereby co-operate to form the control valve.

Formed in the casing are two opposed cylinders 17-18 which are respectively connected by suitable passages 21-22 with chambers 23-24 in the cylinder 15. Disposed in the cylinders are pistons 25-26 which are connected together by the shank 27, forming a single, double-ended piston. The shank 27 of the piston is inclined to the axis of the cylinders, preferably being formed slightly conical in shape for reasons which will hereinafter be set forth. Means are provided for transferring the movement of the piston to the shaft 28, which projects from the casing and which is connected in any suitable manner to the speed controlling means of the apparatus or prime mover to be governed. In the present construction the shaft 28 is provided with crank arms 29 which are pivotally attached to a yoke 31, partly surrounding the shank 27 of the piston and engaging the piston heads 25-26. The shaft 28, in Fig. 5, is connected to the stem 32 of the needle valve through the crank 33 and link 34 and the movement of the shaft is accompanied by a movement of the needle, thereby varying the amount of water projected from the nozzle 35 against the water wheel 36, by which the belt 5 is driven.

50 The piston is operated by fluid, preferably oil, under pressure which is drawn from the reservoir 36 located at the bottom of the casing 2. The reservoir is provided with a filling hopper 37 which also serves as a gage so that the level of the oil in the reservoir may be observed. From the reservoir the oil is drawn through the pipe 38 to the gear pump 39 which is preferably driven by the apparatus or prime mover being governed. From the pump 39 the oil is forced through the pipe 41 into the chamber 42 in the casing, which chamber surrounds the sleeve 14. Means are provided for bypassing the oil from the chamber 42 to the reservoir 36, when the oil is being supplied at

a higher rate than it is being employed to operate the piston. Adjacent chamber 42 is a conduit 43 which opens into the reservoir and the chamber and conduit are connected by a port 44, the opening of which is controlled by a spring pressed plunger 45 arranged in the chamber 42. When the pressure of the oil in chamber 42 passes a certain maximum, the plunger is pressed backward, opening the port 44 and allowing the oil to pass directly into the reservoir.

The sleeve 14 is provided with ports 46 registering with chamber 42 through which the oil passes into the annular space between the sleeve and the body of the piston-valve 8, this space being closed on the top and bottom by the piston heads 12 and 13. The sleeve is also provided with ports 47 connecting the chamber 24 with the interior of the sleeve and ports 48 connecting the chamber 23 with the interior of the sleeve. The opening and closing of the ports 47 and 48 is controlled by the piston heads 12 and 13 on the piston valve 8. The sleeve is also provided with discharge ports 51-52 which establish communication between the interior of the sleeve and the reservoir 36. Secured to the lower end of the sleeve 14 is a pin 53 which engages the inclined surface of the shank 27, thereby causing a movement of the pistons 25-26 to cause or permit a movement of the sleeve 14.

In Fig. 2, the piston valve is shown in the neutral position, that is, the ports 47 and 48 are closed by the piston heads 12 and 13 so that no oil is flowing to or from the cylinders 17-18. As the speed of the prime mover increases, the governor head 6 is drawn down, depressing the piston valve 8 and uncovering the ports 47 and 48. Oil under pressure then flows from the chamber 42 into chamber 23 and thence through conduit 21 to cylinder 17 moving the piston 25-26 to the right, and the oil in cylinder 18 displaced by the movement of the piston flows through conduit 22, chamber 24, ports 47 and 52 to the reservoir. The movement of the piston 25-26 to the right rotates the shaft 28 and thereby reduces the speed of the prime mover and at the same time allows the sleeve 14 to be depressed by the spring 16 to bring the ports 47 and 48 into alignment with the piston heads 12 and 13, thereby closing the ports and replacing the parts in neutral position. The piston 25-26 is, therefore, moved only a sufficient distance to cause the speed of the prime mover to be reduced to the normal. A decrease in the speed of the prime mover will cause the piston valve to raise, thereby causing a movement of the piston 25-26 to the left, which operates through the shaft 28 to increase the speed of the prime mover and also to raise the sleeve to the neutral position. In the application of the governor shown in

Fig. 5, a movement of the piston 25—26 to the right operates to close the needle and decrease the speed of the water wheel and a movement of the piston to the left opens 5 the needle and thereby increases the speed.

At starting, it is necessary to adjust the position of the controlling element of the prime mover, in this instance the needle, by hand until the wheel is brought up to speed, 10 and when the hand control is employed the valve 54 on the pipe 38 should be closed to prevent oil from being forced into the governor. A by-pass valve 57 operated by the hand wheel 58 is provided to establish communication between the cylinders 17 and 18 15 when the shaft is to be rotated by hand. Secured to the shaft 28 is a hand lever crank 68 in which the hand lever 59 is inserted. The hand lever crank is provided with a slot 20 61 concentric with the shaft 28, through which passes a bolt 62 secured to the casing and the bolt is provided with a hand wheel 63 by which the hand lever crank may be clamped in position when starting. After 25 the prime mover and the oil pump are in operation, the valve 54 is opened and the bypass valve 57 is closed and the governor automatically controls the speed of the prime mover. In the water wheel unit shown in 30 Fig. 5, when the wheel is not running, the hand lever crank is clamped in position with the needle closing the nozzle. To start the wheel, the clamp is released and the nozzle gradually opened by the hand lever until 35 the wheel comes up to speed, and then the governor is thrown into operation.

I claim:

1. In a governor, a piston adapted to be moved by fluid under pressure, a valve controlling the flow of such fluid to the piston, 40 means independent of the piston for opening said valve and means on the piston for closing said valve.

2. In a governor, a piston adapted to be moved by fluid under pressure, a valve controlling the flow of such fluid to the piston, means operative by variations in speed of the apparatus being governed to open said valve whereby the piston is moved and 45 means on the piston engaging said valve whereby the movement of the piston closes the valve.

3. In a governor, a piston adapted to be moved by fluid under pressure, a valve controlling the flow of such fluid to the piston, means operative by variations in speed of the apparatus being governed for opening 55 said valve whereby the piston is moved and a surface on the piston inclined to the axis of the piston engaging said valve whereby the movement of the piston closes the valve.

4. In a governor, a piston adapted to be moved by fluid under pressure, a two part valve controlling the flow of such fluid to 60 the piston, means for moving one of said

valve parts to open the valve whereby the piston is moved, and means integral with the piston engaging the other valve part whereby the movement of the piston closes the valve. 70

5. In a governor, a piston adapted to be moved by fluid under pressure, a two part valve controlling the flow of such fluid to the piston, means for moving one of said 75 valve parts to open the valve whereby the piston is moved and means on the piston comprising a surface inclined to the axis of the piston engaging the other valve part, whereby a movement of the piston closes the valve. 80

6. In a governor, a piston adapted to be moved by fluid under pressure, a valve controlling the flow of such fluid to the piston, means for opening said valve whereby the piston is moved and a cone on the piston 85 engaging said valve, whereby the movement of the piston closes the valve.

7. In a governor, a piston adapted to be moved by fluid under pressure, a valve controlling the flow of such fluid to the piston, 90 means operative by variations in speed of the apparatus being governed for operating said valve whereby the piston is moved and means on the piston co-operating with said valve whereby the movement of the piston 95 operates to return the valve to its former condition.

8. In a governor, a piston adapted to be moved by fluid under pressure, a valve controlling the flow of such fluid to the piston, 100 means operative by variations in speed of the apparatus being governed for operating said valve, whereby the piston is moved and a surface on the piston inclined to the axis thereof engaging said valve, whereby the movement of the piston operates to return the valve to its former condition. 105

9. In a governor, the combination of a movable ported sleeve, a valve arranged within the sleeve adapted to be moved relatively thereto by variations in the speed of the apparatus being governed, a piston arranged to be moved by pressure fluid whose flow is controlled by said valve, and means on the piston intermediate its ends for causing the sleeve to move relatively to the valve. 110 115

10. In a governor, a piston adapted to be moved by fluid under pressure, a valve comprising a piston valve and an apertured sleeve for controlling the flow of said fluid 120 to said piston, means operative by variations in speed of the apparatus being governed for moving said piston valve relatively to the sleeve to open the valve whereby the piston is moved, and an inclined surface on the piston engaging said sleeve whereby the movement of the piston causes a movement of the sleeve relative to the piston valve. 125

11. In a governor, a piston adapted to be moved by fluid under pressure, a valve for 130

- controlling the flow of fluid to said piston and means on the piston for operating said valve, any movement of said piston causing a corresponding movement of said valve.
- 5 12. In a governor, a piston adapted to be moved by fluid under pressure, a valve for controlling the flow of the fluid to said piston and an inclined surface on the piston whereby a movement of the piston operates 10 said valve in a corresponding degree.
13. In a governor, a double headed piston, a conical element corresponding in length to the extent of movement of said piston arranged between the piston heads, and a valve 15 for controlling the flow of fluid under pressure to said piston engaging said conical element.
14. In a governor, a casing having opposed cylinders formed therein, pistons in 20 said cylinders, an element having a surface inclined to the axis of the cylinders arranged between and connecting said pistons and a valve for controlling the flow of fluid to said cylinders engaging said element.
- 25 15. In a governor, a casing having opposed cylinders formed therein, pistons in said cylinders, a conical element arranged between and connecting said pistons, a valve for controlling the flow of fluid to said cylinders, means for opening said valve and 30 means engaging said conical element for returning the valve to the closed position.
16. In a governor, a casing having opposed cylinders formed therein, rigidly connected pistons disposed in said cylinders, a valve for controlling the flow of fluid under 35 pressure to and from said cylinders, means for manually moving said pistons and means for by-passing the fluid from one cylinder 40 to the other around the valve.
17. In a governor, a cylinder, a piston in said cylinder adapted to be operated by fluid under pressure, a valve for controlling the flow of said fluid to the cylinder, a chamber 45 surrounding said valve and connected to the source of pressure fluid and a pressure operated relief valve for controlling the pressure of the fluid in said chamber.
18. In a governor, a casing having opposed cylinders formed therein, pistons in 50 said cylinders, a conical element arranged between and connecting said pistons, a shaft connected to said pistons and to the apparatus to be governed, a valve in said casing 55 for controlling the flow of fluid under pressure to said cylinders, means operative by variations in speed of the apparatus being governed for opening said valve, whereby the pistons and shaft are moved, and means connecting the valve with the conical element 60 whereby the movement of the pistons close said valve.
19. In a governor, a casing having opposed cylinders therein, pistons disposed in said cylinders, a conical element arranged between and connecting said pistons, a valve comprising an apertured sleeve and a piston valve for controlling the flow of fluid under pressure to and from said opposed cylinders, 65 means operative by variations in speed of the apparatus being governed for moving said piston valve to admit fluid under pressure to one cylinder and permit the fluid in the opposite cylinder to discharge, whereby the connected pistons are moved, and 70 means on the sleeve engaging said conical element whereby movement of the pistons moves the sleeve to close the inlet and discharge apertures to and from the cylinders.
20. In a governor, a casing having opposed cylinders therein, pistons in said cylinders, a conical element arranged between and connecting said pistons, an apertured sleeve engaging said conical element, chambers in the casing surrounding the sleeve and 75 communicating with the cylinders, a chamber in the casing and surrounding the sleeve, communicating with a source of fluid under pressure, each of said chambers registering with apertures in the sleeve, a piston valve 80 arranged within the sleeve and adapted to be moved by variations in the speed of the apparatus being governed to uncover the apertures in the sleeve whereby fluid under pressure is directed to one cylinder and the fluid in the other cylinder discharges, causing 85 a movement of the pistons and conical element, the movement of the conical element serving to move the sleeve to cause the piston valve to close the apertures therein.
- In testimony whereof, I have hereunto set my hand at San Francisco, California, this 30th day of April, 1915.
- LEOPOLD M. KARNASCH.
